UNITED STATES PATENT OFFICE.

CHARLES D. ORCUTT, OF DAYTON, OHIO.

DESIGN FOR A STOOL.

SPECIFICATION forming part of Design No. 36,264; dated March 31, 1903.

Application filed March 2, 1903. Serial No. 145,843. Term of patent 7 years.

To all whom it may concern:

Be it known that I, CHARLES D. ORCUTT, a citizen of the United States, residing at Dayton, in the county of Montgomery and State of Ohio, have invented a certain new, original, and ornamental Design for a Stool; and I do declare the following to be a full, clear, and exact description of the invention, such as will enable others skilled in the art to which it appertains to make and use the same, reference being had to the accompanying drawing, and to the letters of reference marked thereon, which forms a part of this specification.

15 The drawing is an elevation of a stool made in accordance with my new and ornamental design.

The leading or distinguishing characteristics of my design consists in a leg A, having 20 the form of an animal's leg—for example, a lion's leg—which terminates at the lower end in claws B. The upper end C of the leg ter-

minates in a representation of a lion's face. On each side of said face there is a series of 25 ornamentations C', and below said face there is a series of ornamentations D, which occupy the full width of the leg immediately below the representation of a lion's face. Between each two of said legs there is ornamental 30 skirting having the characteristic designs indicated by E and F, and the upholstered portion of the stool consists of a series of mounds G.

Having described my invention, what I claim as new, and desire to secure by Letters 35 Patent, is—

The ornamental design for a stool as herein shown and described.

In testimony whereof I affix my signature in presence of two witnesses.

CHARLES D. ORCUTT.
